(57) **CLAIM**

The ornamental design for a bullet, as shown and described.

DESCRIPTION

FIG. 1 is an isometric view of a bullet according to my design;

FIG. 2 is a right view thereof;

FIG. 3 is a left view thereof;

FIG. 4 is a back view thereof;

FIG. 5 is a front view thereof;

FIG. 6 is a top view thereof; and,

FIG. 7 is a front view thereof.

The broken lines in the figures illustrate aspects of the bullet which form no part of the claimed design.
